INVENTOR

Martin Parker
BY HIS ATTORNEY,

James F. Williamson

UNITED STATES PATENT OFFICE.

MARTIN PARKER, OF ST. PAUL, MINNESOTA, ASSIGNOR TO PARKER SAFETY HITCH COMPANY, OF ST. PAUL, MINNESOTA, A CORPORATION OF MINNESOTA.

DESIGN FOR A LAZY-HORSE CLEVIS.

59,977.

Specification for Design.

Patented Dec. 13, 1921.

Application filed January 22, 1921. Serial No. 439,300. Term of patent 7 years.

To all whom it may concern:

Be it known that I, MARTIN PARKER, a citizen of the United States, residing at St. Paul, in the county of Ramsey and State of Minnesota, have invented a new, original, and ornamental Design for a Lazy-Horse Clevis, of which the following is a specification, reference being had to the accompanying drawing, forming part thereof.

The single figure is a perspective view of

the lazy horse clevis, showing the same as it appears when detached.

I claim:—

The ornamental design for a lazy horse clevis, as shown.

MARTIN PARKER.
